UNITED STATES PATENT OFFICE.

ERNEST LODGE WILSON, OF PRESTON, ENGLAND, ASSIGNOR OF ONE-HALF TO HAROLD
GEORGE WILSON, OF LONDON, ENGLAND.

CURTAIN-FITTING.

1,339,247.

Specification of Letters Patent.

Patented May 4, 1920.

Application filed September 26, 1919. Serial No. 326,451.

To all whom it may concern:

Be it known that I, ERNEST LODGE WILSON, a subject of the King of Great Britain, residing at Preston, Lancashire, England, have invented certain new and useful Improvements in Curtain-Fittings, of which the following is a specification.

This invention relates to improvements in curtain runners of the type comprising a roller adapted to run on a flat strip race and a frame on which the roller is pivoted and from which the curtain is suspended.

The object of the invention is to provide a runner which can be manufactured very economically and which will run freely on the race even around sharp curves without binding.

According to the invention the frame of the runner is formed of wire which at the upper end passes freely through a roller, and at the upper and lower ends is bent suitably on each side, so that when the frame is canted it makes contact with the race, and avoids binding of the roller which is thereby held in a central position.

In the accompanying drawings:—

Figures 1 to 3 are side elevations illustrating three forms of runner according to the invention fitted with flanged rollers.

Fig. 4 and 5 are respectively a front elevation and plan of part of a flat strip race with runners thereon similar to Fig. 1.

Fig. 6 is a side elevation of a similar form of runner to that shown in Fig. 1, but fitted with a ball roller.

Similar reference numerals represent corresponding parts in all the figures.

In one mode of carrying out the invention the wire frame 1 is bent so as to present four rounded points, 2, 3, 4, and 5 toward the sides of the race 6, two near the upper part and two near the lower part. Each adjacent pair of points are at a less distance apart than the width of the flanged roller 7 between the flanges, so that if the curtain be pulled carelessly so as to cant the runner, one or other of the rounded points touches the side of the race and prevents the flanges touching the race, and as also the roller is of less width over the flanges than the space between the adjacent parts 8, 9, the frame cannot be pulled against the flanges of the roller sufficiently to bind the same. The roller is thus free at all times, even on curved parts of the race.

The lower end 10 of the frame is preferably bent to a V shape or otherwise adapted to hold a curtain ring 11 or hook. The clearance 12 between the ring 11 and lower edge of the track should be less than the depth of the flanges of the rollers to prevent the runner being raised sufficiently to permit of the roller being removed from the race. Similarly the point 3 of the frame 1 of the runner should be sufficiently below the level of the upper edge of the race to prevent the runner being lifted or jerked off laterally of the race, the runner being placed on the race from the end thereof.

The flat strip race 6 may be bent to suit any shape of window or other recess.

When the curtains are to be drawn so as to overlap at the adjacent edges, the race 6 may be in sections as indicated in Figs. 4 and 5, one off-set from the other, stops 16 being screwed one to each of the off-set ends to prevent the runners from leaving the race at these ends. The races may be supported as usual by screws 14 passing through the races and fitted with distance sleeves 15.

In the form of runner shown in Fig. 6 a ball-roller 7 is shown. The wire frame is similar to that before described with reference to Fig. 1, and by it the ball-roller is held free in a central position in the race 6 irrespective of canting of the frame.

I claim—

A curtain runner of the type referred to and comprising a frame formed of wire, a roller freely mounted on the upper part of said frame for the purpose of freely suspending said frame on the edge of a flat strip race, said frame at its upper and lower parts being bent to form pairs of opposed rounded points, the points of each pair being a less distance apart than the width of the aforesaid roller, whereby they engage with the sides of the race when the runner is canted, substantially as and for the purpose hereinbefore set forth.

In testimony whereof I have signed my name to this specification in the presence of two subscribing witnesses.

ERNEST LODGE WILSON.
